UNITED STATES PATENT OFFICE.

ALBERT G. ELVIN, OF SOMERVILLE, NEW JERSEY, AND JOHN L. MOHUN, OF BROOKLYN, NEW YORK; SAID MOHUN ASSIGNOR TO SAID ELVIN.

AXLE-LUBRICATOR.

1,096,161.

Specification of Letters Patent. Patented May 12, 1914.

Application filed November 14, 1913. Serial No. 800,904.

To all whom it may concern:

Be it known that we, ALBERT G. ELVIN, of Somerville, in the county of Somerset and State of New Jersey, and JOHN L. MOHUN, of Brooklyn, in the county of Kings and State of New York, have jointly invented a certain new and useful Improvement in Axle-Lubricators, of which improvement the following is a specification.

10 Our invention relates to axle lubricators of the class or type in which a body of solid lubricant is held in proximity to an axle journal, and adjoining portions thereof successively and continuously fed to the journal by the action of the latter thereon in its rotation, an instance of which is exemplified in Letters Patent Reissue No. 12134, granted and issued to A. G. Elvin aforesaid, under date of July 21, 1908.

20 The object of our invention is to provide means whereby the lubricating device may be securely supported in the axle box cellar and may be inserted in and removed therefrom as may from time to time be required, 25 more readily and expeditiously than under the prior constructions.

The improvement claimed is hereinafter fully set forth.

In the accompanying drawings: Figure 1 30 is a vertical longitudinal central section through an axle box, illustrating an application of our invention, and, Fig. 2, a vertical transverse section through the same, on the line *a a* of Fig. 1.

35 Our invention is herein exemplified as applied in connection with a journal box, 2, which is adapted to be supported on the journal, 1^a, of a locomotive axle, 1, and is, as usual, provided with an upper brass bearing, 3, and a lower lubricant cellar, 4. In the practice of our invention, the lubricant cellar is formed of sheet metal, of rectangular section and open at its bottom, and is interposed between, and fits directly against, 40 the lower legs of the axle box, its lower closure being effected by a binder plate, 5, which is in the form of a comparatively thick plate of cast or wrought metal. The binder plate is fitted below the lubricant cellar, and between lugs, 2^a, on the lower legs of the axle box, being provided with downwardly extending lateral lugs, 5^a, which fit against the lugs, 2^a. An upwardly extending transverse flange, 5^b, is formed on the inner end 55 of the binder plate, said flange abutting

against the inner end of the lubricant casing, and preventing it from coming in contact with the hub of the wheel. The lubricant cellar is held in position in the axle box by bolts, 4^a, passing through the lugs, 2^a, 60 and 5^a. The lubricant cellar is closed at top by a perforated lubricant delivery plate, 6, having downwardly extending lateral flanges, 6^a, which fit against the sides of the lubricant cellar, and similarly extending end 65 plates, 6^b, said lubricant delivery plate being curved in correspondence with, and contacting with, the periphery of the journal, 1^a. A follower plate, 7, is fitted in the cellar, below the lubricant delivery plate, and is 70 pressed upwardly toward the latter by springs, 8, which are interposed between its lower side and the binder plate, 5. The inner end plate of the lubricant delivery plate terminates a short distance below the 75 top of the flange, 5^b, of the binder plate, thereby providing an opening, 6^c, which enables the wall to pass clear of the follower plate when the latter is depressed for the removal of the lubricant delivery plate. 80

The space between the plates, 6 and 7, is, in the operation of the appliance, filled up by a solid block of lubricating material, *x*, which is continuously pressed up to and through the perforations of the plate, 6, 85 and thence to the adjoining periphery of the journal, by the follower plate, 7, and springs, 8. The degree of wear of the lubricant is shown by one or more indicator rods, 9, (two being shown in this instance) 90 which are connected to the follower plate, 7, and pass freely through openings in the binder plate, 5. The lower ends of the rods, 9, are turned into eyes, 9^a, and in addition to acting as indicators, the rods serve to enable the springs, 8, to be manually compressed, when it is desired to remove the lubricant delivery plate from the cellar. 95

The front of the lubricant cellar is closed by a lid, 10, which is hinged by a pin, 10^a, 100 to the front end of the binder plate, 5, and is provided with an eye, 10^b, by which it can be swung about the axis of the hinge pin, for the removal and replacement of the lubricant delivery plate in the renewal of 105 the block of lubricating material. The lid, 10, is held in closed or in open position, as desired, by a spring, 11, secured at its upper end to the lid, and abutting, at and adjoining its free lower end, against one or 110

the other of two flattened bearing faces, which are formed, at substantially a right angle one to the other, on a lug, 5^c, depending from the front end of the binder plate, 5.

When it is desired to remove the lubricant delivery plate from the cellar, it is only necessary to pull the lid, 10, downwardly into the position shown in dotted lines in Fig. 1, and compress the springs, 8, by drawing down the indicator rods, 9. The lubricant delivery plate may then be drawn out through the front of the cellar, as the lower opening, 6^c, at its rear end, enables it to clear the follower plate, 7. The binder plate and lubricant cellar may be removed by drawing out the bolts, 4^a, and if it should stick, by being pinched between the legs of the axle box, it can readily be released by inserting a small jack or spreader between them.

The provision of a lubricant cellar of comparatively light metal, extending entirely between the legs of the axle box, and closed at bottom by a stouter binder plate, without being laterally inclosed by a main cellar, as herein described and shown, attains the substantial advantages, in practice, of reduction of weight and cost, increase in capacity for lubricant, and convenience and expedition in the insertion and removal of the lubricant cellar.

We claim as our invention and desire to secure by Letters Patent:

1. The combination, with an axle box and its bearing, of an open bottomed lubricant cellar, interposed between, and fitting against, the legs of the axle box, a binder plate fitted below, and forming a lower closure for, the lubricant cellar, and means for connecting said binder plate detachably to the axle box.

2. The combination, with an axle box and its bearing, of an open bottomed sheet metal lubricant cellar, interposed between, and fitting against, the legs of the axle box, a binder plate of substantially greater thickness, fitted below, and forming a lower closure for, the lubricant cellar, and means for connecting said binder plate detachably to the axle box.

3. The combination, with an axle box and its bearing, of an open bottomed sheet metal lubricant cellar, interposed between, and fit-

ting against the legs of the axle box, a binder plate of substantially greater thickness, fitted below, and forming a lower closure for, the lubricant cellar, and having lateral lugs, and transverse bolts passing through the lugs of the binder plate and through abutting portions of the axle box.

4. The combination, with an axle box and its bearing, of an open bottomed lubricant cellar, interposed between, and fitting against, the legs of the axle box, a binder plate fitted below, and forming a lower closure for, the lubricant cellar, a lubricating device inclosed in the lubricant cellar, and means for connecting the binder plate detachably to the axle box.

5. The combination, with an axle box, and its bearing, of an open bottomed lubricant cellar, interposed between, and fitting against, the legs of the axle box, a binder plate fitted below, and forming a lower closure for, the lubricant cellar, a door hinged to the binder plate, and closing the front of the lubricant cellar, and means for connecting the binder plate detachably to the axle box.

6. The combination, with an axle box and its bearing, of an open bottomed lubricant cellar, interposed between, and fitting against, the legs of the axle box, a binder plate fitted below, and forming a lower closure for, the lubricant cellar, a door hinged to the binder plate and closing the front of the lubricant cellar, a spring bearing on the binder plate and on said door, and means for connecting the binder plate detachably to the axle box.

7. The combination, with an axle box and its bearing, of an open bottomed lubricant cellar, interposed between, and fitting against, the legs of the axle box, a binder plate fitted below, and forming a lower closure for, the lubricant cellar, a lubricating device inclosed in the lubricant cellar, a door hinged to the binder plate and closing the front of the lubricant cellar, and means for connecting the binder plate detachably to the axle box.

ALBERT G. ELVIN.
JOHN L. MOHUN.
